(57) **CLAIM**

I claim the ornamental design for a steam nozzle, as shown and described.

DESCRIPTION

FIG. 1 is a top perspective view of a steam nozzle according to a new design.

FIG. 2 is a bottom perspective view of the steam nozzle shown in FIG. 1.

FIG. 3 is a front view of the steam nozzle shown in FIG. 1.

FIG. 4 is a rear view of the steam nozzle shown in FIG. 1.

FIG. 5 is a left side view of the steam nozzle shown in FIG. 1.

FIG. 6 is a right side view of the steam nozzle shown in FIG. 1.

FIG. 7 is a top view of the steam nozzle shown in FIG. 1; and,

FIG. 8 is a bottom view of the steam nozzle shown in FIG. 1.

The broken line showing of portions of the steam nozzle is included for the purpose of illustrating and forms no part of the claimed design.
